UNITED STATES PATENT OFFICE.

GEORGE B. WILSON, OF COLUMBUS, OHIO.

CLOTHES-WASHING DEVICE.

No. 927,202.

Specification of Letters Patent.

Patented July 6, 1909.

Application filed January 14, 1909. Serial No. 472,161.

To all whom it may concern:

Be it known that I, GEORGE B. WILSON, a citizen of the United States, residing at Columbus, in the county of Franklin and 5 State of Ohio, have invented a certain new and useful Improvement in Clothes-Washing Devices, of which the following is a specification.

The object of this invention is to provide 10 a cheap, simple and efficient device for washing clothes etc. of the type shown in my Letters Patent of the United States, No. 904,242, November 17th, 1908.

The invention is embodied in the construction 15 hereinafter described and then particularly pointed out in the claims.

In the accompanying drawing illustrating 20 said embodiment—Figure 1 is a view illustrating a fraction of a tub with the device attached, the device itself being illustrated partly in elevation and partly in section. Fig. 2 is a view of the bottom portion of the apparatus. Fig. 3 is a detail partly in section and elevation illustrating the fulcrum 25 connection of the washer operating lever.

Like characters of reference in the several views designate corresponding parts.

The washer head or agitator proper includes two hollow cones of sheet metal, one 30 of them 5 arranged within the other 4 but spaced apart to form a chamber between them. The said cones 4 and 5 are connected by a vertically arranged sheet metal ring 6 extending from the lower edge of the inner 35 one to inner side of the wall of the outer one, the ring being soldered to both. The lower edge of the inner cone and ring 6 project below the plane of the corresponding edge of the outer cone, and the lower edge of the 40 outer cone forms a projecting annular hood, as seen at 4^a, the function of which is to prevent the splashing due principally to the violent blowing of air through perforations 6^a in the ring or wall 6. The upper or small 45 end of the outer cone is open and is clamped between the expanded skirts of two sleeves 7 and 8, the short tubular end of the inner sleeve 7 being threaded into the longer tubular portion of the outer one 8. Above the 50 threaded junction of the two sleeves 7 and 8 the tubular portion of the sleeve 8 forms a valve chamber, the walls of which are provided with air ports 8^a. On the upper end

of the sleeve 8 is a collar 9 having a bore of smaller diameter than that of the valve 55 chamber and in said collar 9 the valve rod 10 works and is guided.

11 designates the valve attached to the rod 10, said valve being of a diameter to fit close against the walls of its chamber. The 60 valve 11 is, if desired, suitably packed and its vertical play in the chamber is such as to open the ports 8^a when the rod is raised, and to close the said ports when the rod is depressed. The rod 10 operates both the 65 valve and the washer head.

17 designates a bell-shaped deflector supported by lugs cast integral with the sleeve 7, one of which lugs is shown at 17^a. The function of this deflector is to direct the air 70 forced upward through the open apex end of the inner cone downward toward the perforations 6^a. There is an annular series of the vents 6^a in the ring or wall 6, and the lower portion of the inner side of the cone 5 75 is provided with a screen consisting of a series of parallel bars 5^a.

The rod 10 is hingedly connected to a long lever 12 of wood which is provided at one end with a suitable handle and said lever 80 is fulcrumed at its other end on a suitable standard, the latter being detachably secured by a clamp screw 13 to the tub. The standard referred to is composed of a part 15 that has two legs, one of which receives the 85 said clamp screw 13, and a part 16 that is swiveled at 15^a to the part 15. The part 16 has an opening 16^a through which the end of the lever 12 is passed. The upper side of the fulcrumed end of the lever 12 is furnished 90 with a metallic bar 12^a having a series of notches, and the upper portion of the part 16 is made with an edge 16^b adapted to engage any of said notches. The upper side of the end of the lever 12 above the notched 95 bar 12^a is provided with a rail 12^b that is offset from the notched bar, or stands at such a distance from the notched bar that when the lever is in about the horizontal position the upper portion of the part 16 is confined 100 with the edge 16^b engaged with one of the aforesaid notches. The upper side of the part 16 above the engaging edge 16^b is rounded, as seen at 16^c, so that the lever 12 can be rocked without seriously springing 105 the rail 12^b. But the handle can be readily

forced, by slightly raising it, from one bearing to another so that the washer head or agitating device can, with the aid of its swiveled connection, be pressed down on the clothes in all parts of the tub.

In practice the washer head or agitator is reciprocated, up and down, on the clothes in the water or suds in the tub. In the upward movement of the device the ports 8^a are opened and air drawn in or admitted to the chamber between the cones. When the washer head is forced quickly down and depressed into clothes and water or suds in the tub the ports 8^a are closed, the air confined within the inner cone and chamber between the cones is compressed, and because this air seeks a state of ordinary atmospheric pressure, some of it passes out through the openings 6^a in the wall 6 and through the water or suds in the space between the hood 4^a and said wall 6 and through the clothes standing across that space. The downward pressure of the washer head also forces water and suds up through clothes brought against the screen in the lower portion of the inner cone.

In the upward movement of the washer head the clothes are promptly liberated from the head or agitator by reason of the admission of air through the ports 8^a to the chamber between the two cones and to the interior of the inner cone.

What I claim and desire to secure by Letters Patent is:

1. In a clothes washer, the combination of the two hollow cones located one within the other and spaced apart to form a chamber, said cones being open at their apices, a wall provided with perforations joining the lower portions of said cones, and a wall at the upper portion of the outer cone forming a valve chamber having an air port, and a movable valve in said valve chamber to open

and close said air port, substantially as described.

2. In a clothes washer, the combination of two hollow cones located one within the other and spaced apart to form a chamber, said cones being open at their apices, a wall provided with perforations joining the lower portions of said cones, a screen across the interior of the inner of said cones, a wall at the upper portion of the outer cone forming a valve chamber having an air port, and a movable valve in said valve chamber to open and close said air port.

3. In a clothes washer, the combination of two hollow cones located one within the other and spaced apart to form a chamber, said cones being open at their apices, a wall provided with perforations joining the lower portions of said cones, a deflector between the apices of the two cones, a wall at the upper portion of the outer cone forming a valve chamber provided with an air port, and a movable valve in said valve chamber to open and close said air port.

4. In a clothes washer, the combination of two hollow cones located one within the other and spaced apart to form a chamber, said cones being open at their apices, a perforated upright wall connecting the lower edge of the inner cone with the inner side of the wall of the outer cone above the lower edge of the outer cone, thereby providing a projecting hood around said upright wall, a wall at the upper end of the outer cone forming a valve chamber provided with an air port, and a movable valve in said valve chamber adapted to open and close said air port.

GEORGE B. WILSON.
